CLAIM

The ornamental design for a spiral fishing lure, as shown and described.

DESCRIPTION

FIG. 1 is a perspective view of my new design for a fishing lure;

FIG. 2 is a top plan view of the lure of FIG. 1;

FIG. 3 is a bottom plan view of the lure of FIG. 1 with the lure rotated end for end;

FIG. 4 is a side elevational view of the lure of FIG. 1;

FIG. 5 is a side elevational view of the lure of FIG. 1 with the lure rotated end for end;

FIG. 6 is a front elevational view of the lure of FIG. 1 as seen from the line attaching end of the lure;

FIG. 7 is a rear elevational view of the lure of FIG. 1 as seen from the hook end;

FIG. 8 is a perspective view of an alternative embodiment of my new fishing lure design including etched surface ornamentation on the top and bottom surfaces and wherein a number of cupped holes are also let through the body of the lure;

FIG. 9 is a top plan view of the lure of FIG. 8; and

FIG. 10 is a bottom plan view of the lure of FIG. 8 with the lure rotated end for end.
